(57) **CLAIM**

The ornamental design for a stowable laundry caddy, as shown and described.

DESCRIPTION

FIG. 1 is a front perspective view of a stowable laundry caddy showing my new design in an extended position;

FIG. 2 is a left side elevational view thereof, the right side view being a mirror image;

FIG. 3 is a rear elevational view thereof, the front elevational view being substantially a mirror image;

FIG. 4 is a top plan view thereof;

FIG. 5 is a bottom plan view thereof;

FIG. 6 is a bottom plan view thereof, the top plan view being substantially a mirror image, it being understood that said FIG. 6 is shown in an alternate, stowable position for clarity of disclosure;

FIG. 7 is a left side elevational view of FIG. 6, the right side view being a mirror image; and,

FIG. 8 is a front elevational view of FIG. 6, the rear elevational view being substantially a mirror image.
